J. G. Schelter & Giesecke in Leipzig.

UNITED STATES PATENT OFFICE.

GEORG F. GIESECKE, OF LEIPSIC, SAXONY, GERMANY.

DESIGN FOR A FONT OF TYPE.

SPECIFICATION forming part of Design No. 19,419, dated November 12, 1889.

Application filed October 18, 1889. Serial No. 327,461. Term of patent 7 years.

To all whom it may concern:

Be it known that I, GEORG F. GIESECKE, a citizen of Saxony, residing at Leipsic, Saxony, Germany, have invented and produced a new 5 and original Design for a Font of Type; and I do declare the following to be a full, clear, and exact description of the same, reference being had to the accompanying drawing, forming a part thereof.

10 The accompanying illustration is an impression of a font of type, showing the capital letters and figures.

15 The leading features of the design consist in a letter or figure having a flat face, across which are lines of shading diminishing in intensity from the top to the bottom, heavy shading away from the upper left-hand corner, a fine light line beyond the heavy shading, with a space between, and delicate tracery 20 lines about each letter but not about the figures.

25 Referring in detail to the letters, the A, B, D, E, F, H, I, K, L, M, N, P, R, T, V, W, X, Y, and Z have to the right of their straight lines a heavy shading commensurate in length with such straight lines and of full width their entire length. The B, D, E, F, G, J, P, R, and U have to the right of their combined straight and curved lines a heavy shading 30 commensurate with such lines flush with the ends of the straight portions and tapering off

gradually along the curved portions. The shading of the upper part of the Z and the front upper part of the T is commensurate with the portion of the letter. The shading 35 of the rear upper part of the T tapers. The B and J have to the right of their full curved lines shading which tapers at one end and is full at the other. The C, G, O, Q, and S have at the right of their curved lines shading 40 which tapers at both ends, except the curve at the lower right end of the S, which ends flush at the left. All of these letters except the I have delicate lines of tracery about them diverging from the lines of the letter. 45

Referring to the figures, the straight lines have to their right heavy shading commensurate with the lines and with the ends flush. The curved lines have shading similar to those in the letters. Beyond all the shading 50 is a fine light line, between which and the shading is a light space.

What I claim is—

The design for a font of type, as herein shown and described. 55

In testimony whereof I affix my signature in presence of two witnesses.

GEORG F. GIESECKE.

Witnesses:

CARL BORNGRAEBER,
JOHN K. TETLOW.
